UNITED STATES PATENT OFFICE.

GEORGE J. FLIEHMANN, OF ST. LOUIS, MISSOURI, ASSIGNOR OF ONE-HALF
TO GEORGE ITTNER.

DESIGN FOR A TAG-HOLDER.

SPECIFICATION forming part of Design No. 29,329, dated September 13, 1898.

Application filed July 30, 1898. Serial No. 687,367. Term of patent 3½ years.

To all whom it may concern:

Be it known that I, GEORGE J. FLIEHMANN, a citizen of the United States, residing at St. Louis, Missouri, have invented and produced
5 a new and original Design for Tag-Holders, of which the following is a specification.

Figure 1 is a front elevation of a tag-holder embodying my new design. Fig. 2 is a section on line 2 2 of Fig. 1. Fig. 3 is a trans-
10 rverse section on line 3 3 of Fig. 1. Fig. 4 is a side view of Fig. 1.

As shown in the drawings, the essential feature of my design for tag-holders consists of a body portion 4, of rectangular configura-
15 tion. Upon each side thereof are inturned flanges 6 and 7 and a corresponding one 5 at

one end, said flanges providing a space beneath them and the body portion, the adjacent terminals of the side and end flanges being mitered.

8 is a tongue forming a continuation of the body portion and bent back upon the same and slightly removed therefrom, the terminal of said tongue being slightly curved outward.

What I wish to claim is—
25 The design for a tag-holder as herein shown and described.

GEORGE J. FLIEHMANN.
